DESIGN FOR A LIGHT FIXTURE FOR LIQUID DISPENSING APPARATUS

William M. Griffin, Fort Wayne, Ind., assignor to
The Wayne Pump Company, Fort Wayne, Ind.,
a corporation of Maryland

Application April 21, 1937, Serial No. 68,911

Term of patent 14 years

To all whom it may concern:

Be it known that I, William M. Griffin, a citizen of the United States, residing at Fort Wayne, in the county of Allen and State of Indiana, have invented a new, original, and ornamental Design for a Light Fixture for Liquid Dispensing Apparatus, of which the following is a specification, reference being had to the accompanying drawing, forming a part thereof.

Figure 1 is a front elevational view of a light

fixture for liquid dispensing apparatus, showing my new design;

Figure 2 is a side elevation of said light fixture;

Figure 3 is a bottom plan view of said light fixture.

I claim:

The ornamental design for a light fixture for liquid dispensing apparatus as shown.

WILLIAM M. GRIFFIN.
